John L. Snyder, Jr., Wapakoneta, Ohio, assignor to The Standard Churn Company, Wapako-
neta, Ohio, a corporation of Ohio

Application December 5, 1945, Serial No. 124,392

Term of patent 14 years

(Cl. D58—25)

To all whom it may concern:

Be it known that I, John L. Snyder, Jr., a citizen of the United States of America and a resident of Wapakoneta, in the county of Auglaize and State of Ohio, have invented a new, original, and ornamental Design for a Jar or Similar Article, of which the following is the specification, reference being had to the accompanying drawing, forming a part thereof.

I claim:

The ornamental design for a jar or similar article, substantially as shown.
